UNITED STATES PATENT OFFICE.

EUGENE J. RAY, OF BEVERLY, MASSACHUSETTS, ASSIGNOR, BY MESNE ASSIGNMENTS,
TO UNITED SHOE MACHINERY CORPORATION, OF PATERSON, NEW JERSEY, A COR-
PORATION OF NEW JERSEY.

BUTTONHOLE-SEWING MACHINE.

1,303,400.

Specification of Letters Patent.

Patented May 13, 1919.

Application filed May 19, 1915, Serial No. 29,166. Renewed July 25, 1918. Serial No. 246,782.

To all whom it may concern:

Be it known that I, EUGENE J. RAY, a citizen of the United States, residing at Beverly, in the county of Essex and State 5 of Massachusetts, have invented certain new and useful Improvements in Buttonhole-Sewing Machines; and I do hereby declare the following to be a full, clear, and exact description of the invention, such as will 10 enable others skilled in the art to which it appertains to make and use the same.

The invention relates to buttonhole sewing machines, and more particularly to an under thread tension mechanism for such 15 machines.

In doing certain classes of work it is desirable to use a comparatively heavy tension on the under thread, and in some cases the desired tension may be heavy enough to interfere with the proper or easy feed of the 20 work between the cutting and sewing of successive buttonholes.

It is the object of the present invention to provide novel and improved mechanism for 25 automatically releasing the tension on the under thread at the end of the sewing, and for reapplying the tension at the beginning of the sewing. To this end the invention consists in the features of construction and 30 combinations of parts hereinafter described and referred to in the claims.

The invention will be readily understood from an inspection of the accompanying drawings and the following detailed description 35 of the mechanism illustrated therein.

In the drawings, Figure 1 is a vertical sectional view showing so much of a buttonhole sewing machine as is necessary to 40 illustrate the application of the present invention thereto, and Fig. 2 is a detail plan view showing the under thread mechanism and a part of the clamp carrier.

In the drawings the invention is shown as 45 embodied in a buttonhole sewing machine having substantially the construction and mode of operation of the machine shown and described in Patent No. 1,063,880, dated June 3, 1913. In this machine the stitch 50 forming mechanism comprises an upper needle 2 eccentrically mounted in a vertically reciprocating needle bar 4, an under needle 6, and a looper 8. The upper needle bar and the under needle and looper are mounted 55 respectively in a rotary carrier 10 and a ro-

tary turret 12 which are rotated during the sewing about the end and eye of the buttonhole. The work is held by clamps 14 mounted on supporting plates 16 which are in turn mounted on a clamp carrier 18. The 60 clamp carrier is moved longitudinally of the buttonhole to bring the work into register with the buttonhole cutter 20, or with the stitch forming mechanism, and to feed the work during the sewing by a cam groove 65 formed in the cam gear 22, which makes one revolution for each cycle of the machine. The clamp carrier is moved laterally, and the stitch forming mechanism is rotated during the sewing, through suitable connections from a gear 24 which makes one revolution during the sewing of a buttonhole. 70

The tension mechanism for the under thread comprises a stationary disk 26 secured upon the turret 12, and a cooperating 75 disk 28 mounted upon a stud 30 and pressed against the disk 26 by a spring 32, the tension of which may be adjusted by the nut 34. The disk 28 is of such a diameter that it projects beyond the edge of the disk 26 and 80 into the path of a finger 36 which is secured to the clamp carrier 18. The under thread is led from the thread supply through suitable guides up through the hollow link 38 which forms a part of the mechanism 85 for actuating the under needle and looper, thence between the tension disks 26 and 28 through a thread guide 40 on the turret, through a thread guide 42 on the under needle arm, and thence to the under 90 needle.

When the machine is at rest the work clamp is in position to register with the cutter, and the tension releasing finger 36 is in engagement with the disk 28, and holds 95 it away from the disk 26 against the tension of the spring 32, so that the tension on the under thread is released. When the machine is started, the clamp is closed and the cutter operated to cut the buttonhole 100 slit, and then the clamp carrier moves forward to bring the buttonhole slit into register with the stitch forming mechanism. The forward movement of the clamp withdraws the finger 36 from engagement with 105 the disk 28, so that the tension is applied to the under thread by the time that the buttonhole slit is brought into register with the sewing mechanism, and the sewing mechanism is started. At the completion of the 110

sewing the sewing mechanism is stopped, and the rotation of the turret is arrested with the turret in the position indicated in Fig. 2. The turret remains in this position 5 until the beginning of the sewing of the next buttonhole. After the sewing has been completed, and the sewing mechanism and turret stopped, the clamp carriage is retracted to bring the work clamps into position 10 to register with the cutter, and the machine is then stopped with the parts in the position indicated in Fig. 1. During this movement of the clamp carrier from sewing to cutting position the tension releasing finger 36 again engages the tension disk 28 and releases the tension upon the under thread, so that the work may be moved 15 easily and freely into position for the cutting and sewing of the next buttonhole.

Having explained the nature and object 20 of the invention, and specifically described one form of mechanism in which it may be embodied, what is claimed is:—

1. A buttonhole sewing machine, having, 25 in combination, stitch forming mechanism comprising upper and under thread mecha-

nism, a work clamp carrier, a rotary turret carrying the under thread mechanism, mechanism for relatively actuating the stitch forming mechanism and clamp carrier to 30 sew about a buttonhole, an under thread tension device mounted on the turret comprising a movable thread engaging member, and a finger on the clamp carrier engaged with and disengaged from said movable member by the relative movement of the clamp and stitch forming mechanism to apply the tension at the beginning of the sewing and to relieve the tension at the completion of the sewing. 35

2. A buttonhole sewing machine, having, in combination, stitch forming mechanism comprising upper and under thread mechanisms, a rotary turret carrying the under thread mechanism, a longitudinal and laterally movable work clamp carrier, an under thread tension device on the turret comprising a movable disk, and a finger on the carrier engaged with and disengaged from the disk by the reciprocation of the carrier. 40 45
